UNITED STATES PATENT OFFICE.

GEORGE T. CHERINGTON, OF WAUKEGAN, ILLINOIS.

AUTOMATIC STOP FOR PHONOGRAHS.

Application filed May 26, 1920. Serial No. 384,316.

To all whom it may concern:

Be it known that I, GEORGE T. CHERINGTON, a citizen of the United States, and resident of Waukegan, county of Lake, and 5 State of Illinois, have invented a certain new and useful Improvement in Automatic Stops for Phonographs, of which the following is a specification.

My invention relates to that class of phonographs which use a flat record which rests upon a turn table, and has for its object to provide a new and improved stop for the machine when it has finished playing; and has for its further object to provide a new 15 and improved means of covering the turn table.

The stops on machines of this character with which I am familiar, require setting and it is sometimes difficult to set them 20 without either destroying the point of the needle or scratching the record, if the needle has a metallic point. Furthermore, it frequently occurs that the operator either forgets or neglects to set the stop, with the 25 result that sometimes the record is stopped before it is finished playing, and other times it does not stop at all.

My invention when applied to a phonograph, insures the complete playing of every 30 record, and also the stopping of further rotation of the turn table when the playing is finished.

My improved means of covering the turn table is designed to avoid the necessity of 35 gluing the felt which is usually employed for a cover, to the top of the turn table; it generally being the case that this felt only extends to the top.

My means of accomplishing the foregoing 40 objects may be more readily understood by having reference to the accompanying drawings which are hereunto annexed and are a part of this specification, in which—

Fig. 1 is a fragmentary view, partly in 45 section, of a top of a turn table cabinet, showing my improvement.

Fig. 2 is a top or plan view of the device 50 portions of the record and turn table, being broken away to more clearly show the interior construction.

Fig. 3 is a fragmentary detail view of the trigger.

As shown in the drawings, the motor board 1 is provided with an opening through 55 which passes the turn table shaft 2, which

carries the turn table 3. The tone arm 4 carries the usual reproducer or sound box 5 to which is secured the needle 6 in the usual and customary manner.

Mounted upon the lower side of the turn 60 table, and concentric therewith is a disk 7. As illustrated, it is secured to the turn table by means of rivets 8. This disk 7 is provided with a peripheral flange 9 which depends downwardly therefrom. 65

Mounted upon the motor board 1 is a pivot 10 which may be secured in place by any suitable or convenient means. Upon the pivot 10 is oscillatively mounted a trigger 11, one end 12 of which extends beyond the 70 periphery of the turn table 3; the other end is provided with two lugs 13 and 14 which are so arranged that when the opening 15 in the trigger 11 is mounted on the pivot 10, the lug 13 will be within the downwardly 75 depending peripheral flange 9, and the other lug 14 will be without said flange.

In the lugs 13 and 14 are mounted pins, 80 16 and 17 which carry rollers 18 and 19 preferably formed of felt, which act as brake-shoes, as will be hereinafter set forth.

A rod 20 is fixedly attached to the tone arm 4 and is movable therewith. It necessarily follows, therefore, that when the tone arm swings upon its center, that the rod 20 85 will be brought into contact with the end 12 of the trigger 11. This will swing the trigger upon the pin or pivot 10 to the position shown by the dotted lines in Fig. 2, in which position, as will be apparent, the brake-shoes 90 18 and 19 bear against the inner and outer sides of the peripheral flange 9 and effectually prevent its further rotation.

A flat spring 21 is secured to the motor board by means of a screw 22 and bears 95 against the edge of the trigger 11 serving to hold it normally in the position shown in Fig. 1, so that the turn table is free to rotate unless the trigger is moved to the position indicated by the dotted lines in Fig. 2. 100

Adjacent the screw 22 I mount a pin 23 which serves as a fulcrum over which the spring 21 is bent by the trigger as it swings upon the pivot 10 when the rod 20 on the tone arm 4 contacts with the end 12. 105

It may be found desirable in practice to supply a detent 24 mounted in the motor board to prevent the trigger from swinging too far in the opposite direction, when the tone arm is swung to the position shown in 110

Fig. 1 in full lines, and the pressure of the spring would operate to move the trigger on its pivot.

It will be apparent from the drawing that 5 the rod 20 on the tone arm 4 cannot actuate the trigger unless the needle moves beyond the edge of the medallion in the center of the record. In order for this to occur, I provide a template with a scroll or french curve 10 edge. This template is provided with an opening which is fitted to and coincides with the size of the turn table shaft 2, so that when the record is in position the template may be placed on the record and a groove 15 formed in the record by following the edge of the template with a sharp instrument, with the result that when the record travels inwardly to the edge of the medallion, it will then pass in on the scroll 25 as shown 20 in Fig. 1, until it reaches point 26, in which case it will occupy the position as shown in the dotted lines in the said figure, when the trigger will have been swung to one side on its pivot and the shoes 18 and 19 are caused 25 to exert a braking power against the further rotation of the turn table.

It will be obvious from the foregoing description that in this way it is impossible for the automatic stop to operate until the 30 record has finished playing. Furthermore, that it cannot continue to rotate after the needle reaches the point 26 on the scroll 25 without the rod 20 actuating the end 12 of the trigger 11, and bringing the machine to 35 a full stop, thus entirely eliminating the human equation insofar as the stopping of the machine is concerned.

Having described my invention what I regard as new and desire to secure by Letters 40 Patent is:

1. The combination with a phonograph having a motor board, a tone arm, reproducer and needle therefor, and a turn table, of a member secured to the underside of said 45 turn table, a peripheral flange on said member, a record having a spiral groove extending from the inner groove of the playing grooves to a point adjacent the center of

said record, a pivoted trigger mounted on the motor board adjacent the periphery of 50 said flange, brake-shoes mounted on said trigger on each side of said flange, a fixed member secured to the tone arm, which engages the trigger when the needle is adjacent the center of the record, and thus 55 causes the brake-shoes to engage the flange.

2. The combination with a phonograph having a motor board, a tone arm, reproducer and needle therefor, and a turn table, of a member secured to the underside of said 60 turn table, a peripheral flange on said member, a record having a spiral groove extending from the inner groove of the playing grooves to a point adjacent the center of said record, a pivoted trigger mounted on the 65 motor board adjacent the periphery of said flange, brake-shoes mounted on said trigger on each side of said flange, a fixed member secured to the tone arm, which engages the trigger when the needle is adjacent the 70 center of the record, and thus causes the brake-shoes to engage the flange, and a spring to hold said shoes normally out of engagement with said flange.

3. The combination with a phonograph 75 having a motor board, a tone arm, reproducer and needle therefor, and a turn table, of a member to be gripped carried by the turn table, means to grip said member on two sides of the member to be gripped, and 80 means secured to the tone arm to cause the said gripping means to operate when the needle travels to a point inside of the playing grooves.

4. The combination with a phonograph 85 having a motor board, a tone arm, reproducer and needle therefor, and a turn table, of a member to be gripped, means to grip said member on two sides of the member to be gripped, and means secured to the tone 90 arm to cause the said gripping means to operate when the needle travels to a point inside of the playing grooves.

In testimony whereof, I have signed the foregoing specification.

GEORGE T. CHERINGTON.
